UNITED STATES PATENT OFFICE.

AUGUSTE CLEMENT GRETEN AND FRANCOIS MUSMAN, OF LUXEMBURG, LUXEMBURG.

FOUR-STROKE-CYCLE INTERNAL-COMBUSTION ENGINE.

1,354,101.

Specification of Letters Patent. Patented Sept. 28, 1920.

Application filed November 14, 1919. Serial No. 337,925.

To all whom it may concern:

Be it known that we, AUGUSTE CLEMENT GRETEN and FRANCOIS MUSMAN, subjects of the Grand Duchess of Luxemburg, residing, respectively, at Boulevard Exterieur 23 and Place Giillaume 12, Luxemburg, Luxemburg, have invented certain new and useful Improvements in Four-Stroke-Cycle Internal-Combustion Engines, of which the following is a specification.

The present invention relates to a four stroke cycle internal combustion engine with cylindrical sleeve valve and the novelty of the invention consists in that a ring of exhaust ports, a ring of inlet ports for the oil gas and a ring of inlet ports for compressed air are provided on the cylinder, and corresponding rings of ports are provided on the sleeve valve, said rings being positioned in such a manner that, during a four stroke cycle beginning after the expansion period the following results are secured:

(a) The exhaust gases flow from the cylinder into the exhaust duct through the registering rings of exhaust ports provided on sleeve valve and cylinder;

(b) The fraction of combustion gases remaining in the cylinder and combustion chamber are wholly expelled by compressed air entering through the lower ring of inlet ports provided on the cylinder and the intermediate ring of ports of the slide valve, which rings of ports are registering;

(c) The cylinder and the combustion chamber are wholly filled with fresh air;

(d) The said fresh air with the exception of the fraction contained in the combustion chamber, is expelled by the piston through the registering upper exhaust ports on sleeve and cylinder, during the upward stroke of the piston.

(e) A small amount of fresh air is again sucked by the piston into the cylinder through the exhaust ports during the beginning of the downward stroke of the piston.

(f) A vacuum is formed in the cylinder during a further downward motion of the piston, all ports being closed.

(g) Oil gas from the carbureter is fed to the cylinder through the registering in-

termediate ring of ports of both cylinder and sleeve valve.

(h) Compressed air enters the cylinder through the lower registering rings of ports of cylinder and sleeve valve.

The above results will clearly result from the following description, with reference to the accompanying drawing, given by way of example, in which:

Figure 1 is an axial section of a four stroke cycle internal combustion engine.

Figs. 2 to 9 are diagrammatic views showing various relative positions of the cylinder, sleeve valve, piston and crank shafts, during a complete four stroke cycle.

In these figures:

1 is the cylinder of the motor, 3, the piston. Between cylinder 1 and piston 3 is engaged the cylindrical sleeve valve 2 provided with the three rings of ports 4, 5 and 6, while the cylinder is provided with corresponding rings of ports 7, 8 and 9.

10 is the exhaust duct for the burned gases, from which they escape to the atmospheric air.

11 is the gas admission duct, 12 the compressed air admission duct.

15 is the crank pin on the motor shaft, 16 the crank pin on the half time shaft 14.

Following the motion of the various movable parts during one complete cycle, we observe that Fig. 2 corresponds to the end of the expansion period.

Sleeve valve 2 and piston 3 are moving downward; crank pin 15 is near its outer dead center and pin 16 of the half time shaft crank is moving in the same direction as pin 15. All ports are still closed. Referring to Fig. 3, pin 15 has reached its outer dead center; the upper or exhaust ports 4 of the sleeve-valve uncover the corresponding ports 7 of the cylinder and the hot combustion gases escape from the cylinder into exhaust duct 10. This is the exhaust stage. The intermediate ports 5 of the sleeve valve now uncover the lower ports 9 of the cylinder, through which compressed air from duct 11 enters the cylinder, the piston 3 having reached its lowermost position. The cylinder 1 is filled with compressed air and cooled; the larger portion of

said air escapes through the registering exhaust ducts 4 and 7, expelling every remaining particle of combustion gases. This may be considered as an extension of the above 5 exhaust stage.

It may be observed that, owing to the plurality of large ports all around the cylinder and sleeve valve, the combustion gases are quickly evacuated and a large amount of 10 compressed air flows through the cylinder and combustion chamber.

Following the motion of both pins 15 and 16, we observe that, while pin 16 of sleeve-valve 2 is reaching its outer dead center, 15 crank pin 15 moves upward, whereby the piston expels the fresh air from the cylinder 1 up to the combustion chamber, in which fresh air remains. This stage may also be considered as a part of the exhaust. 20 The exhaust of the combustion gases thus is performed during three stages, which occur during the motion performed by the pins 15 and 16 between the positions shown in Figs. 3 and 4.

25 During the latter stage, fresh air remains in the combustion chamber; this stage may also be considered as the beginning of the suction period.

Pin 15 has reached its inner dead center 30 (Fig. 4) and the piston now begins its downward stroke, whereby it sucks a small amount of air from the registering exhaust ports 4 and 7 into the cylinder until the sleeve valve 2, which is sliding upward, 35 closes the ports 7. This is a stage of suction of fresh air, following the above mentioned beginning of suction of fresh air.

Now the ports 7 being closed, and the piston moving downward, (Fig. 5), a 40 vacuum is produced within the cylinder, until crank pin 15, during its forward motion, reaches the position shown in Fig. 6; pin 16 is moving upward and the intermediate ports 5 of sleeve valve are registering 45 with the intermediate ports 8 of the cylinder. The latter occurs in a position of the parts between those shown in Figs. 6 and 7, and oil gas from the carbureter enters the cylinder, filling the latter. This stage 50 is a third part of the suction period. The piston, following its downward motion, pin 15 reaches its outer center Fig. 8, whereby the piston is in its lowermost position. At the same time valve sleeve 2 moving upward, 55 the lower ports 6 and 9 of sleeve and cylinder register, and compressed air from duct 12 flows to the cylinder. This stage is a fourth part of the suction period.

Finally the piston, moving upward from 60 its outer dead center, and all ports being closed, the explosive mixture is compressed until the explosion occurs (Fig. 9), whereby the pin 15 reaches its inner dead center, after which the piston is forced downward

while the sleeve is already moving downward; having passed its inner dead center. 65

Having now fully described our said invention, what we claim and desire to secure by Letters Patent, is:

1. An internal combustion engine comprising a cylinder having an exhaust passage, an inlet passage and an air passage, a piston mounted in the cylinder to reciprocate, a sleeve mounted in the cylinder between the piston and cylinder and formed 70 with passages corresponding to those in said cylinder, and means for operating the sleeve, to hold the exhaust passage open during the first part of the downward movement of the piston, to close all the passages during another portion of the downward movement of the piston, subsequently opening the intake passage during farther downward movement of the piston, and thereafter opening the air passage at the lower limit 75 of movement of the piston, and then closing all passages during the next entire upward movement of said piston.

2. An internal combustion engine comprising a cylinder having exhaust ports in the upper end portion thereof, air ports in the lower end portion and gas inlet ports between the aforementioned ports, a single sleeve having three sets of ports formed therein and a piston mounted in the sleeve 90 for reciprocating motion, one set of ports in the sleeve opening the exhaust ports in the cylinder during the upward and partial downward movement of the piston, the second set of ports in the sleeve opening and 95 closing the air ports in the cylinder while the exhaust ports are open, the second set of ports subsequently opening the inlet ports of the cylinder while the other ports are closed, and the third set of ports in the 100 sleeve opening the air ports in the cylinder subsequent to the opening and closing of the 105 inlet ports.

3. An internal combustion engine comprising a cylinder, having an exhaust passage, an inlet passage, and a compressed air passage, a sleeve mounted in said cylinder having corresponding passages, and means for operating said sleeve to open and close the passages, said means opening the 110 exhaust passage and subsequently the air passage when the piston is at the lower limit of the explosion stroke, closing the air passage as the piston moves upward, and holding the exhaust passage open during the entire upward movement of the piston and a portion of the following downward movement.

4. An internal combustion engine comprising a cylinder, having an exhaust passage, an inlet passage, and a compressed air passage, a sleeve slidably mounted in said cylinder and having three sets of passages 125

corresponding with the passages in the cylinder, a piston mounted for reciprocation in said sleeve, and means for operating the sleeve to cause one set of passages to open the exhaust passage, and a second set of passages to open the air passage when the piston is at the lower limit of the explosion stroke, subsequently closing the air passage as the piston moves upward, and holding 10 the exhaust passage open during the entire

upward movement of the piston and a portion of the following downward movement.

In testimony whereof we have hereunto set our hands in presence of two witnesses.

AUGUSTE CLEMENT GRETEN.

FRANÇOIS MUSMAN.
